George M. Graham,
by Robert Burns, Attorney

UNITED STATES PATENT OFFICE.

GEORGE M. GRAHAM, OF CHICAGO, ILLINOIS, ASSIGNOR TO G. A. EDWARD KOHLER,
OF CHICAGO, ILLINOIS.

WIRE-SPLICER.

No. 875,803.

Specification of Letters Patent.

Patented Jan. 7, 1908.

Application filed June 1, 1907. Serial No. 376,807.

To all whom it may concern:

Be it known that I, GEORGE M. GRAHAM, a citizen of the United States of America, and a resident of Chicago, in the county of 5 Cook and State of Illinois, have invented certain new and useful Improvements in Wire-Splacers, of which the following is a specification.

This invention relates to ties or couplings 10 for uniting the adjacent ends of wires or rods together, and which is more especially adapted for securing together sections of the wire strands used in the reinforced concrete construction which forms the subject matter 15 of my prior application for Letters Patent, Serial No. 349,684, filed December 27, 1906, and the present improvement has for its object to provide a simple and efficient structural arrangement and combination of parts 20 whereby a very substantial connection is effected in a very ready and convenient manner, all as will hereinafter more fully appear.

In the accompanying drawings: Figure 1, is a vertical section of a tie or coupling embodying the present invention. Fig. 2, is a top view of the same. Fig. 3, is a bottom view of the same.

Similar numerals of reference indicate like parts in the different views.

30 Referring to the drawings, 1 represents the body of the tie of a hexagon or other suitable form and formed with a central screw-threaded orifice 2, in manner similar to the nut of an ordinary screw bolt; and in the production 35 of the present ties, nuts of the required size may be economically employed as elements in such manufacture.

3 are duplicate holes formed in adjacent and parallel relation in the body 1, and in a 40 direction transverse to that of the screw-threaded orifice 2, and opening into the same. It is a material part of the present invention 45 that the diameter of the screw-threaded orifice 2, be much greater than the combined diameter of the holes 3, for reasons herein-after set forth.

The holes 3 are adapted to receive the ends 4 and 5 of the wires to be joined; and to this end the respective wire ends are passed in 50 opposite directions through the respective holes as shown. It is within the scope of the present invention to merge the two holes into a single oblong orifice adapted to receive the wire ends, such construction however only

adds to the cost without increasing the efficiency of the device.

6 is a clamping plug formed with a screw-threaded periphery corresponding to and fitting the screw-threaded orifice 2 of the tie body; such plug is provided at one end with 60 a non-circular portion or head 7 to afford means for effecting manual rotation of the plug, while at its other end said plug is formed with an obtuse cone projection 8 of greater diameter than the combined width of 65 the wires to be joined and adapted to enter the space between the wire ends 4 and 5 and, as the clamping plug is screwed into the tie body, force the wire parts within the orifice 2, downward and outward into contact or 70 engagement with the screw threads of the screw threaded orifice 2 to effect a very rigid and substantial locking of the wire ends within the tie body.

Having thus fully described my said invention what I claim as new and desire to secure by Letters Patent, is:—

1. A wire splicer, comprising a nut having a screw threaded orifice of greater diameter than the wire parts to be spliced, and transverse alined holes intersecting the screw threaded orifice and adapted to receive the wire parts, and a clamping plug having a screw threaded periphery and a cone projection adapted to enter the space between the wire parts and force the latter forward and outward into contact with the screw threads of the screw threaded orifice.

2. A wire splicer, comprising a nut having a screw threaded orifice of greater diameter 90 than the wire parts to be spliced, and transverse alined holes intersecting the screw threaded orifice and adapted to receive the wire parts, and a clamping plug having a screw threaded periphery fitting in the screw 95 threaded orifice and a cone projection of greater diameter than the combined width of the wire parts and adapted to enter the space between the wire parts and force the latter forward and outward into contact 100 with the screw threads of the screw threaded orifice.

Signed at Chicago, Illinois, this 23rd day of May, 1907.

GEORGE M. GRAHAM.

Witnesses:

ROBERT BURNS,
FRANK S. REID.
